UNITED STATES PATENT OFFICE.

CHARLES C. SPENGLER, OF ROCKFORD, AND HENRY T. SIDWAY, OF CHICAGO, ILLINOIS,
ASSIGNORS TO HENRY T. SIDWAY & COMPANY, OF CHICAGO, ILLINOIS, A CORPORATION OF ILLINOIS.

HEATING APPLIANCE.

956,783.

Specification of Letters Patent.

Patented May 3, 1910.

Application filed January 25, 1908. Serial No. 473,974.

To all whom it may concern:

Be it known that we, CHARLES C. SPENGLER and HENRY T. SIDWAY, citizens of the United States, residing at Rockford, in the county of Winnebago, and Chicago, in the county of Cook, and State of Illinois, respectively, have invented certain new and useful Improvements in Heating Appliances, of which the following is a specification.

This invention relates to devices intended to be placed over the burner of a gas or similar stove, for the purpose of distributing the heat from said burner to a plurality of cooking utensils.

The object of the invention is to improve the construction of such devices with the view to increasing their efficiency and simplicity and reducing their cost of manufacture.

In the accompanying drawings, Figure 1 is a top plan view of a heating appliance embodying the features of our invention. Fig. 2 is an underside view. Fig. 3 is a section on line 3-3 of Fig. 1.

That embodiment of the invention which is herein shown comprises a top plate 1 and a bottom plate 2, said plates being secured together by means such as rivets 3, and being spaced apart by a member 4. In this instance, the member 4 is a strip of band iron held in place by the rivets 3 and constituting the side walls of the device. The ends of the member 4 are secured together by means of one or more rivets 5. The top plate 1, as herein shown, is larger than the lower plate to provide increased space for supporting the cooking utensils.

Centrally of the lower plate 2 is an opening 6 through which the heated gases from the stove burner enter the device and in the upper plate 1 is a plurality of openings 7, in this instance, three, over which may be set cooking utensils, etc. In order to space the utensil from the top plate a short distance so that said utensil will not prevent a draft through the device, raised portions 8 are provided, said portions, in this instance, being integral with the top plate 1. Extending into one or more of the openings 7 are lugs 9 which serve as a support for utensils of smaller dimensions than the diameter of said openings.

The means for distributing the heated gases entering the opening 6 to all of the

openings 7 comprises a deflector 10, shown in the drawings as of pyramidal form, said deflector having a substantially circular base 11 by which it is secured to the upper plate 1. In this instance, the deflector 10 is three-sided, each of its sides facing one of the openings in the top plate. Certain of the rivets 3 are preferably arranged to hold the middle portions of the sides of the wall 4 inwardly toward the deflector 10, as shown, the corners of said deflector lying adjacent said inwardly extending middle portions, thereby assisting in deflecting substantially all the heat entering the appliance toward the openings 7. A rivet 12 connects the apex of the deflector with the plate 1. If desired, a plate 13 of heat-insulating material may be placed between said deflector base and said plate 1, and the interior of the deflector may be filled with asbestos or other suitable insulating material.

Pivotedly mounted in the side wall 4 is a damper 14 for cutting off heat from one of the openings 7 when such opening is not in use. The top plate 1 may have openings 15 therein adapted to receive a lifter of common form, guide lugs 16 struck down from said plate adjacent the opening 16 serving to hold the appliance steady with relation to said lifter.

We claim as our invention:

1. A heating appliance comprising two plates, the lower plate having an opening centrally thereof, the upper plate having a plurality of openings therein, side walls lying between said plates, means connecting said plates together, said connecting means holding said side walls in place, and a heat deflector of pyramidal form fixed to said upper plate above the opening in said lower plate, certain of said connecting means being positioned to hold the middle portions of said side walls inwardly toward said deflector, the sides of said deflector facing the openings in said upper plate and the corners of said deflector lying adjacent said inwardly extending portions of said side walls.

2. A heating appliance comprising two substantially triangular plates, the lower plate having an opening centrally thereof, the upper plate having an opening in each of its corners, side walls lying between said plates, means connecting said plates together, said connecting means holding said side walls in place, and a heat deflector of three-

- sided pyramidal form fixed to said upper plate above the opening in said lower plate, each of the sides of said deflector facing one of the openings in said upper plate.
- 5 3. A heating appliance comprising a hollow structure having an opening in its lower wall and a plurality of openings in its upper wall, the side walls of the structure extending inwardly toward the center of the
- 10 structure at points between the upper openings, and a pyramidal heat deflector in said structure positioned so that each of the sides of said deflector will deflect heat entering

the opening in the lower wall toward one of the openings in the upper wall.
